DISPENSER

Earl R. Crebbs, San Francisco, Calif.

Application September 30, 1940, Serial No. 358,945

2 Claims. (Cl. 242—55.5)

My invention relates to dispensers and more particularly to a refillable dispenser in which rolled sheet material may be mounted, and torn off along predetermined tear-lines.

Among the objects of my invention are:

To provide a dispenser for rolled sheet material having tear-lines therein; to provide a dispenser for rolled sheet material that is easily and quickly refilled; to provide a dispenser for materials such as paper towels, sanitary toilet seat covers, and the like, joined by tear-lines; and to provide a simple, relatively cheap and efficient refillable dispenser for rolled sheet material.

Other objects of my invention will be apparent or will be specifically pointed out in the description forming a part of this specification, but I do not limit myself to the embodiment of the invention herein described, as various forms may be adopted within the scope of the claims.

In the drawing:

Fig. 1 is a perspective view of one preferred form of my invention showing the position of the sheet as it is being withdrawn from the dispenser.

Fig. 2 is a cross-sectional view of the dispenser and contained roll.

Fig. 3 is a view, partly in section and partly in elevation, of the end spring arrangement, with the cover closed.

Fig. 4 is a view similar to Fig. 3 with the cover opened.

My invention may be more fully understood by a direct reference to the drawing, wherein the dispenser body comprises a back 1 having indentations 2 therein whereby the back 1 may be applied to a vertical wall. Indentations 2 have screw apertures 3 therein, through which screws may be passed and affixed to the wall directly, or a flat button may be cemented to the wall, this button having a bolt passing through aperture 3. In either case, the dispenser is adapted to be firmly attached to the vertical wall. The body also comprises a top portion 4, to which a cover 5 is applied by hinges 6, this cover being preferably of cylindrical contour. Cover 5 is maintained in a predetermined closed position by an end portion 7 thereof overlapping body sizes 8, and the lower portion of the cover terminates in fingers 10 adjacent each lower corner of the cover for use in tearing off paper sheets 11 from a strip roll 13 wound on a core 12 with the customary tear-lines between sheets. Core 12 is mounted in the dispenser on end pivots 15 and

16, one pivot 15 being mounted on spring 17 attached to one side wall, the other pivot 16 being solidly riveted to the other side wall.

The bottom 20 of the dispenser body extends forward beneath a mounted roll 13 but terminates short of the vertical plane touching the front periphery of the core 12, so that irrespective of the amount of paper on the roll the end of the strip, when depending downwardly, will not touch bottom 20.

Cover 5 is held in closed position and also in an open position by the use of U-shaped double-acting springs 21 positioned at each end of the dispenser body adjacent and inside of each side

15 wall 8. These springs operate as shown in Figs. 3 and 4. Each spring is a tempered wire somewhat semicircular in shape, and has one end 22 hooked into back 1 of the dispenser body, the spring then taking a forward course against

20 the inside of side wall 8. The spring then passes through a side wall slot 24 to terminate in an opposite end 25 hooked into cover 5 on the inside thereof. The spring is under an expanding stress at all times, and inasmuch as the cover

25 end 25 of the spring passes around the hinge axis during the movement of the cover from closed to open position, the shortest distances between the two ends will be when the cover is closed and when the cover is open, as shown

30 by broken line 26 in Fig. 4. Thus, the cover is held tightly closed by the spring and when opened is held open by the same spring against the wall on which the dispenser is mounted.

In operation, a strip roll 13 of sheets 11 separated by tear-lines and wound on core 12 is inserted in the dispenser by opening the cover, inserting pivot 16 in a pivot aperture 27 in one end of the core, and then sliding the opposite end of

40 the core over spring-mounted pivot 15 until pivot 15 enters the pivot aperture 27 in that end of the core. This can be done without manually holding the cover, due to the fact that the cover springs 21 hold the cover open. The cover is then closed with the end of the rolled strip depending from the dispenser in contact with fingers 10.

To tear sheets 11 from the roll the end of the strip is grasped in the hand, pulling the strip downwardly and outwardly until fingers 10 enter the tear-lines and start the separation of a unit 11. The outward force needed to tear a unit 11 from the remainder of the roll is resisted by the springs 21 and the unit is torn off. Due to the fact that the springs 21 are used to hold the cover firmly against the remainder of the body of the dispenser, no zigzag arrangement of the de-

pendent strip is necessary as the cover does not tend to move outwardly and the springs are made to have sufficient tension to oppose the tearing forces. Inasmuch as the bottom 20 of the container does not enter into the tearing of the strip in any manner, the tearing is accomplished with equal facility whether or not the roll is a full roll or a roll that is nearly empty. The strip depending from a full roll will meet the fingers 10 at an angle which is only slightly different from that of the strip depending from a nearly empty roll, as I prefer to bring the cover fingers 10 around underneath the roll to terminate at or slightly to the rear of the vertical plane touching the front periphery of core 12. Thus, whether or not the roll is full or nearly empty the units 11 are removed therefrom with equal facility and the depending strip is unrolled only in contact with fingers 10.

I claim:

1. Container means for dispensing sheet material rolled on a core and having tear lines extending across said sheet comprising a body having a back portion adapted to be attached to a vertical wall, and side portions having inner pins upon which said core may be mounted, a bottom portion extending forwardly to terminate slightly to the rear of a vertical plane passing through

a line joining said inner pins, and a cover hinged to the top of said body portion and extending forwardly around and resting on the edges of said side portions and terminating in tear line intersecting fingers below the level of said bottom and slightly forward of said vertical plane.

2. In a refillable dispenser of rolled sheet material, a body having a vertical portion adapted to be attached to a vertical wall, side walls attached to said vertical portion and inwardly carrying opposed roll mounting means thereon, and a cover hinged to the top of vertical portion and extending above, forwardly and downwardly around a roll mounted on said mounting means and resting in closed position on the top and front edges of said side walls, and a roughly semi-circular wire spring having one end inserted into said vertical portion, and the other end inserted into said cover, said spring passing around said hinge on the interior of said body closely adjacent one side wall and being under diametrical tension at both open and closed positions of said cover, said spring being maintained in a vertical plane by passing through a spring restraining aperture in the top edge of the adjacent side wall.

EARL R. CREBBS.
